UNITED STATES PATENT OFFICE

JOHN E. BELL, DECEASED, LATE OF BROOKLYN, NEW YORK, BY LOLA R. BELL, EXECUTRIX, OF BROOKLYN, NEW YORK, AND EDWARD W. ISOM, OF LOCUST VALLEY, NEW YORK, ASSIGNORS TO SINCLAIR REFINING COMPANY, OF NEW YORK, N. Y., A CORPORATION OF MAINE

ART OF CRACKING HYDROCARBON OILS

Application filed January 22, 1925. Serial No. 3,984.

This invention relates to improvements in cracking heavier hydrocarbon oils, such as gas oil, for the production of lighter hydrocarbon oils, such as gasoline or pressure 5 distillate, by distillation under pressure.

In cracking hydrocarbon oils by distillation under pressure, the oil is heated to a cracking temperature under pressure and the heavier oil, or a portion thereof, is broken down or "cracked" with the formation of lighter oils which are vaporized and driven off. The cracking operation takes place gradually and progressively, part of the cracked constituents escaping as pressure 10 distillate and part of the heavier cracked constituents remaining and mixing with the charge of oil in the pressure still. A small amount of asphaltic, or pitch-like constituents, or heavy tar is also formed by the cracking operation. This tar remains in the charge and gradually accumulates due to the vaporization of cracked constituents and to the progressive formation of tar constituents. This tar accumulating in the oil in the still tends 15 to deposit on the heating surfaces of the still and in contact therewith tends to form a carbonaceous deposit thereon closely adhering thereto. Such carbonaceous materials and the heavy tar accumulating in the still charge 20 are poor conductors of heat and when deposited on the heating surfaces of the still which are externally exposed to heating gases interfere with heat transfer and insulate the wall from the protection afforded by the oil 25 so that the walls of the still are apt to become overheated, the temperature of the metal of the heat transferring wall increasing over that of the oil to an extent dependent upon the thickness of the deposit and the amount 30 of heat externally delivered to the wall from the heating gases. As a consequence the pressure still must frequently be shut down for cleaning or the temperature of the heating gases must be reduced below that which is 35 most efficient. There is also considerable danger involved due to possible bursting of the heat transferring walls at overheated points. The heating surfaces over which heating gases are first circulated are exposed 40 to the highest temperature of the heating

gases and absorb the greatest amount of heat, and these surfaces are most apt to suffer. Heating surfaces immediately adjacent the furnace employed to heat the pressure still may also absorb a large amount of heat by direct radiation from the furnace.

According to the present invention, the heating surfaces of the pressure still are protected by rapidly circulating the still charge thereover by mechanical forcing means, such as a pump, and reflux or fresh oil or admixed reflux and fresh oil is employed in a particularly advantageous way to regulate the composition of the circulating oil, particularly with reference to its content of crackable constituents and carbon and heavy tarry matter, as it is circulated over the heating surfaces of the still. By employing mechanical forcing means for circulating the oil the rapidity of the circulation is promoted. With more rapid circulation the rate of heat transfer from the heating surfaces to the oil is increased and the capacity of the still is increased. Rapid absorption of heat from the heated walls of the still is thus effected, reducing any tendency of the surfaces to become overheated by carrying the heat off in the oil and by maintaining the heating surfaces at a temperature more nearly approximating that of the circulating oil, while at the same time the rapid mechanical circulation of the oil assists in preventing or materially reducing the formation of carbonaceous deposits on the heating surfaces and assists in carrying carbon and tar constituents with the circulating oil.

According to the present invention, reflux, or fresh oil, or admixed reflux and fresh oil, is first circulated in heat exchanging relation with the heating gases at their highest temperature before they are circulated over other heating surfaces of the pressure still, and, as the light cracked constituents are vaporized and the oil loses its content of crackable hydrocarbons and as the concentration of carbon and tar constituents increases, the oil is circulated in heat exchanging relation with heating gases which have been tempered and reduced in temperature by heat exchange with the reflux or fresh oil

by circulating the oil of increased tar content over more remote heating surfaces of the pressure still. As vaporization occurs, the tar and carbon formed by the cracking reaction remain in the still charge, and when the vaporized constituents are subjected to a refluxing operation the reflux is substantially free from carbon and tar constituents. Fresh oil, likewise, is free from tar and carbon formed by the cracking reaction, and it usually contains a larger amount of more easily cracked constituents. When reflux, or fresh oil, or admixed reflux and fresh oil are admixed with a part of the still charge, they assist in reducing the concentration of carbon and tar constituents and in maintaining the concentration of tar constituents below saturation in that part of the charge. The heating gases while at highest temperature are thus passed over heating surfaces which are in contact with circulating oil relatively free of tar constituents, or in which the concentration of tar is least, and as the tar concentration increases the oil is circulated over heating surfaces in contact with progressively tempered and cooler heating gases. The lighter crackable constituents of the reflux or fresh oil are also subjected to advantageous cracking conditions by heat exchange with the hottest heating gases. The heating surfaces of the pressure still most apt to suffer are thus protected by rapid absorption of the heat transferred therethrough in heating and cracking the oil constituents of the reflux or fresh oil circulated thereover and this heat available at high temperature is advantageously employed in a useful cracking operation rather than in the further cracking of tar constituents while a reduced concentration of tar constituents is maintained in the oil circulating over these initial heating surfaces preventing or materially reducing the formation of carbonaceous deposits thereon. The heat available in the heating gases, the temperature of which has been lowered by the heat absorbed in heating and cracking the reflux, or fresh oil, or admixed reflux and fresh oil, is then further employed to advantage in cracking the circulating oil as tar constituents accumulate therein.

In one particularly advantageous way of carrying out the present invention, the vapors from the cracking operation are subjected to a refluxing operation in direct contact with fresh oil and the reflux and admixed fresh oil are employed to protect the heating surfaces of the pressure still while at the same time the reflux and admixed fresh oil are subjected to advantageous cracking conditions. The reflux and admixed fresh oil are thus first circulated in heat exchanging relation with the heating gases at their highest temperature before they are passed over other heating surfaces

of the pressure still, and, as the light cracked constituents are vaporized and the oil loses its content of crackable hydrocarbons and as the concentration of tar constituents increases, the oil is circulated in heat exchanging relation with heating gases which have been tempered and reduced in temperature by heat exchange with the reflux and admixed fresh oil by passing the oil of increased tar content over more remote heating surfaces of the pressure still. The heating gases while at highest temperature are thus passed over heating surfaces which are in contact with oil relatively free of tar constituents, or in which the concentration of tar is least, and as the tar concentration increases the oil is passed over heating surfaces in contact with progressively tempered and cooler heating gases. The lighter crackable constituents of the reflux and admixed fresh oil are also subjected to advantageous cracking conditions by heat exchange with the hottest heating gases. The heating surfaces of the pressure still most apt to suffer are thus protected by absorption of the heat transferred therethrough in heating and cracking the oil constituents of the reflux and admixed fresh oil and this heat available at high temperature is advantageously employed in a useful cracking operation rather than in the further cracking of tar constituents while a reduced concentration of tar constituents is maintained in the oil in contact with these initial heating surfaces preventing or materially reducing the formation of carbonaceous deposits thereon. The heat available in the heating gases, the temperature of which has been lowered by the heat absorbed in heating and cracking the reflux and admixed fresh oil, is then further employed to advantage in cracking the oil as tar constituents accumulate therein.

In carrying out the invention, the heating surfaces of the pressure still may be further protected and the heating of the pressure still charge equalized by providing progressively increased areas of heat transfer between the oil and the heating gases as the tar content of the circulating oil increases and as the temperature of the heating gases decreases. The heating effect is thus equalized by increasing the area of heat transfer as the temperature of the heating gases decreases while an increased area of heating surface is provided in contact with the circulating oil containing an increased tar content where deposition is most likely to occur. Where the same volumetric circulation is maintained throughout the operation, progressive increase in the area of heat transfer also provides for most rapid circulation of the oil over the initial heating surfaces with which the heating gases are first brought in heat exchanging relation, further promoting rapid absorption of heat from the hot still walls in

contact with the hottest heating gases. The mechanical forcing means may also be arranged and operated to maintain most rapid circulation over the initial heating surfaces whether or not the area of heat transfer is increased as the tar content of the circulating oil increases. The tar content of the pressure still charge may also be controlled and reduced by withdrawing tar from one or more portions of the still charge where the tar tends to accumulate.

The process of the invention may be carried out in a series of stages or cycles, with mechanical circulation of the oil in each stage or cycle from a body of the oil in heat exchanging relation with the heating gases and back to the body, and transferring oil to successive stages as its tar content increases, circulating heating gases in heat exchanging relation with the oil in the stages or cycles successively in the order of increasing tar content, and circulating reflux, or fresh oil, or admixed reflux and fresh oil, through the stage or cycle in which the oil is subjected to heat exchange with the heating gases of highest temperature. In one aspect, the process of the present invention may be considered a process in which the reflux, or fresh oil, or admixed reflux and fresh oil, are first subjected to a more or less intense cracking treatment and then, as tar and carbon accumulate in the oil, to a digestion treatment in which the cracking temperature may advantageously be maintained by mechanically circulating oil from a body of the oil in heat exchanging relation with the heating gases from the initial cracking treatment and back to the body.

While the invention is of particular advantage where the same stream of heating gases is employed for heating the oil in the successive stages of the process as the temperature of the heating gases is progressively reduced, certain advantages of the invention may be obtained by employing heating gases of separately regulated temperature in the successive stages, employing hotter heating gases for initially heating and cracking the reflux, or fresh oil, or admixed reflux and fresh oil, and progressively cooler heating gases for heating the circulating oil of progressively increasing tar content in the successive stages.

The invention will be further described in connection with the accompanying drawings which illustrate in a diagrammatic way one form of apparatus adapted for carrying out the process of the invention. The apparatus illustrated is described and claimed in an application filed April 8, 1921, Serial No. 459,555, which has matured into Patent 1,547,994, and the process of the present invention is of special value and application in connection with pressure stills of this general character. The process of the invention

may, however, be carried out in other and different apparatus.

In the accompanying drawings:

Fig. 1 represents a pressure still, in elevation and section with parts broken away and with a condenser diagrammatically shown, adapted for carrying out the process of the invention.

Fig. 2 is a fragmentary section on an enlarged scale on line 2—2 of Fig. 1, and

Fig. 3 is a fragmentary section on an enlarged scale on line 3—3 of Fig. 1.

The pressure still illustrated comprises a drum 4 and a series of tubular heating elements communicating therewith arranged in the heating flue of a furnace 5. The heating flue comprises a series of connected vertical flues 6, 7, 8 and 9, the flue 6 also connecting with the furnace 5 and the flue 9 with a stack flue 10. The flues are arranged so that the heating gases from the furnace are passed successively therethrough to the stack. A draft tube 11 is arranged for withdrawing waste heating gases from a point adjacent the exit of the heating flue 9 and returning them to the flue 6 for tempering the heating gases fresh from the furnace 5 in the flue 6. The draft tube may be operated by a steam jet or other suitable forcing means. By returning waste heating gases in this way, the heating gases are tempered in the first heating flue, the volume and rate of circulation of the heating gases through the heating flues is increased, and the available heat in the recycled gases may be further utilized. By-passes 12 and 13 provided with regulating dampers 14 and 15 are provided for further controlling the distribution of heat in the several flues.

The still drum 4 is provided internally with a series of partitions 16, 17 and 18 dividing the drum into a series of compartments A, B, C and D and a corresponding series of heating elements separately communicating with each of these compartments are arranged in the heating flues. The heating element connected to compartment A is arranged in flue 6, that is the flue through which the heating gases are first passed, the heating element of the next compartment B in the next flue 7, and so on, the heating element connected to the last compartment D being arranged in the last heating flue 9 through which the coolest heating gases are circulated. The partitions in the drum do not completely shut off the compartments from each other but extend a short distance above the normal liquid level therein leaving a common vapor space in the upper part of the drum. Overflow pipes 19, 20 and 21 are arranged for progressively transferring oil to successive compartments in the series, and these pipes are provided with bell caps to prevent transfer of surface scum and froth to successive compartments.

Each of the heating elements connected to the respective compartments comprises these similar groups of heating tubes. Each of these groups comprises a header 22, a series of upwardly inclined tubes 23 arranged through the heating flue for heat exchange with the heating gases therein, connecting headers 24, another series of upwardly inclined tubes 25 arranged through the heating flue, and a header 26. In order to facilitate cleaning and repair the headers are arranged outside of the heating flues and are formed with plugged hand holes in alignment with the heating tubes. In order to equalize the heating effect in the several heaters, to promote relatively more rapid circulation in the first heaters, and to provide an increased area of heat transfer as the tar content of the oil increases, as will presently appear in more detail, the heat transferring area of the several heaters is progressively increased as the temperature of the heating gases declines. In the apparatus illustrated, the heater connected to the first compartment A has four tubes in each group, that connected to compartment B eight tubes, that connected to compartment C twelve tubes and that connected to the last compartment D sixteen tubes.

Arranged above the drum 4 is a reflux tower 27 adapted to receive vapors from the vapor space of the drum 4 and to discharge reflux into the first compartment A connected to the heating element arranged in heat exchanging relation with the hottest heating gases. A connection 28 is provided for introducing fresh oil into the upper part of the reflux tower over the baffles therein and in direct contact with the vapors therein. Another connection 29 discharging into the first compartment A is also provided for the introduction of fresh oil directly thereto. The vapors escape from the reflux tower through vapor line 30 to a condenser diagrammatically illustrated at 31. The pressure in the still may be reduced and controlled by a regulating valve 32 arranged between the reflux tower and the condenser or by a valve 33 arranged beyond the condenser. Where fresh oil is introduced through the reflux tower, the reflux tower may be covered or protected with suitable heat insulation, such as an asbestos or mineral wool jacket. Or the reflux tower may be arranged to operate by external cooling, such as air cooling. The still drum is advantageously insulated against heat loss.

The headers 22 in each group are connected to a common horizontal header 34 which is in turn connected through pipe 35 to the discharge side of a circulating pump. The headers 26 in each group are arranged to discharge into the corresponding compartment in the drum 4. A connection 36 is also provided between each compartment in the drum

and the inlet side of the circulating pump discharging through the heater connected to that compartment. In Figs. 1 and 3 of the drawings the connections between the communicating compartments, pumps and heating elements are designated by the reference characters 35 and 36 with the letter corresponding to the compartment with which they communicate appended. A separate pump may be employed for each of the compartments. It is advantageous, however, to arrange the pumps in a common casing and to use a common driving means as shown in the drawings. The pumps shown in the drawings are of the rotary piston type, sometimes known as Connersville pumps, and are particularly adapted for use in carrying out the process of the invention but it will be apparent that pumps of other suitable construction adapted to handle hot oil at the cracking temperature may be employed. The pumps shown are independent and the oil is separately circulated through each of them, partitions 37 being arranged between the several pump chambers to confine the oil in each circulating stream to that stream. A valved outlet 38 is provided in the connection 35D for discharging tar from the pressure still during the cracking operation.

In carrying out the process of the invention in the apparatus illustrated, the still is initially charged with oil through connection 29 while the pumps are in operation, the oil successively overflowing into the adjacent compartments as the preceding compartments and circulating connections are filled, and brought to the cracking temperature and pressure in the usual way. The oil in the first compartment A and the connected heating element first reaches the cracking temperature and the oil in the successive compartments and heaters reaches the cracking temperature in order. The pumps are continuously operated during the operation to maintain a forced and rapid circulation of the oil from each of the several compartments through the connected heating element and back to the same compartment. Each of the several pumps withdraws oil from the compartment to which it is connected through connection 36 and forces it upwardly through the corresponding heating element back to the compartment. The pressure employed may differ with different charging stocks and for the production of different pressure distillates. With gas oil character charging stocks for the production of gasoline character distillates, pressures up to 90 to 125 pounds per square inch or more may be employed. In cracking a kerosene character charging stock to produce a gasoline character distillate, considerably higher pressures may be used, for example, pressures up to 300 pounds per square inch or more may be employed.

After the still charge is brought to the cracking temperature and pressure, the cracked vapors rise from the several compartments and pass upwardly through the reflux tower 27, and the introduction of fresh oil is begun. Fresh oil may be introduced either through connection 28 or through connection 29 or through both connections. In any case, the reflux and fresh oil are introduced into compartment A. As the reflux and fresh oil are introduced into compartment A, oil from this first compartment which has been deprived of a part of its crackable constituents and contains some tar constituents overflows into the second compartment B where it is further cracked and a further part of its components are vaporized. In the same way oil is transferred from compartment B to compartment C and from compartment C to compartment D as the cracked constituents are vaporized and as the tar accumulates, the oil in the successive compartments containing less and less of the original oil constituents and more and more heavy tarry constituents. Tar may be withdrawn from the last compartment D during the progress of the cracking operation continuously or from time to time through connection 35D. The introduction of fresh oil into the reflux tower may be controlled to regulate the refluxing operation. Where no tar, or only a relatively small amount of tar is withdrawn, the amount of fresh oil introduced into the reflux tower may correspond approximately to the amount of distillate taken off or may be somewhat in excess of this amount. Where larger amounts of tar are withdrawn, the still charge is maintained by the introduction of an increased amount of fresh oil, and the fresh oil supplied may be divided and introduced partly into the reflux tower and partly into compartment A directly or may all be introduced directly into compartment A.

The heating gases from the furnace 5 are passed successively over the heating elements connected to compartments A, B, C and D in order, so that the oil in the first compartment A, including the reflux and fresh oil, is mechanically circulated in heat exchanging relation with the heating gases of highest temperature, that in the second compartment B is mechanically circulated in heat exchanging relation with heating gases of a somewhat lower temperature, and so on. The heat absorbed by the oil circulating from and to the first compartment A is employed to crack the oil constituents of the reflux and fresh oil and this oil is rapidly circulated over the initial heating surfaces protecting them against the highest temperature of the heating gases, and as the tar content of the oil increases it is transferred to successive compartments where it is circulated in heat exchange with heating gases of progressive- ly lower temperature. At the same time the heating effect in the successive compartments is equalized by the progressively increased area of heat transfer provided, and the difficulties and dangers incident to the formation of carbonaceous deposits are materially reduced due both to the decreased temperature of the heating gases and the increased area of heat transfer and consequent reduction in the rate of heat transfer per unit of area. In all of the heating elements the absorption of heat by the rapidly circulating oil protects the heating surfaces, particularly in the first where the heating element is exposed to the hottest heating gases and where the circulating oil contains the reflux and fresh oil and the least content of tar, and the most rapid circulation is maintained.

It will thus be seen that the present invention provides an improved method of cracking hydrocarbon oils by distillation under pressure in externally heated stills in which the oil is mechanically circulated over the heating surfaces of the still to promote absorption of heat in the oil and to protect the heating surfaces and in which the oil circulated over the heating surfaces in contact with the hottest heating gases consists of fresh oil and reflux while the heating gases cooled and tempered in this initial heating operation are employed to further heat and crack the oil as carbon and tar constituents accumulate in it. The oil circulating through the still thus initially consists of fresh oil and reflux and is first circulated in heat exchanging relation with the hottest heating gases, and, as the fresh oil and reflux constituents are cracked and vaporized and as the circulating oil becomes heavier and carbon and tar constituents accumulate therein, the oil is mechanically circulated in heat exchanging relation with the cooler heating gases from the preceding heating operation.

It will further be seen that the present invention provides an improved method of cracking hydrocarbon oils by distillation under pressure in externally heated pressure stills in which fresh oil is supplied to the cracking operation and in which the fresh oil is first employed to promote and control a refluxing operation to which the vapors from the pressure still are subjected and then, in admixture with the reflux, is mechanically circulated over heating surfaces of the pressure still to heat exchange with the hottest heating gases while the lighter crackable constituents are subjected to particularly advantageous cracking conditions.

One of the important advantages of the present invention is that it enables the cracking operation to be carried out over a prolonged period without, however, decreasing the rate of cracking by reducing the temperature of the heating gases or otherwise. Another important advantage of the inven-

tion is that it enables an improved application of the heating gases to the cracking operation so that both the efficiency and the capacity of the pressure still may be increased.

5 What is claimed as new and desired to be secured by Letters Patent of the United States is:

1. An improved method of cracking hydrocarbon oils, which comprises mechanically 10 circulating the oil in a series of cycles and transferring the oil to successive cycles as the tar content of the oil increases, heating the oil to a cracking temperature under pressure by circulating heating gases in heat exchanging relation successively with the oil in the cycles in the order of increasing tar content, maintaining progressively increasing areas of heat transfer between the heating gases and the oil in the successive cycles in 15 the same order, subjecting the vapors from the cracking operation to a refluxing operation, and returning the reflux to the first cycle in which the tar concentration is least.

2. An improved method of cracking hydrocarbon oils, which comprises heating a body 25 of oil to a cracking temperature under pressure by circulating oil from the body in heat exchanging relation with heating gases and back to the body, subjecting the vapors from the cracking operation to a refluxing operation, and circulating the reflux at a more rapid rate in heat exchanging relation with the heating gases before the heating gases are brought into heat exchanging relation 30 with the oil in the first said heating operation.

3. An improved method of cracking hydrocarbon oils, which comprises circulating the oil in each of a series of cycles and heating the oil to a cracking temperature under 40 pressure in each cycle, transferring oil to successive cycles as the tar-content of the oil increases, subjecting the vapors formed to a refluxing operation, returning the reflux to the first of said cycles, circulating heating gases for supplying the heat absorbed in the cracking operation first in heat exchanging relation with the oil in the cycle to which the reflux and fresh oil are returned and thereafter over the successive cycles, and maintaining the most rapid circulation in the cycle to which the reflux and fresh oil are returned.

4. An improved method of cracking hydrocarbon oils, which comprises circulating the oil in each of a series of cycles and heating the oil to a cracking temperature under pressure in each cycle, transferring oil to successive cycles as the tar-content of the oil increases, subjecting the vapors formed to a 55 refluxing operation in direct contact with fresh oil, returning the reflux and admixed fresh oil to the first of said cycles, circulating heating gases for supplying the heat absorbed in the cracking operation first in heat exchanging relation with the oil in the cycle

to which the reflux and fresh oil are returned and thereafter over the successive cycles, and maintaining the most rapid circulation in the cycle to which the reflux and fresh oil are returned.

5. An improved method of cracking hydrocarbon oils, which comprises heating a body of oil to a cracking temperature under pressure by circulating oil from the body in heat exchanging relation with heating gases and back to the body, circulating fresh oil at a more rapid rate in heat exchanging relation with the heating gases before the heating gases are brought into heat exchanging relation with the oil in the first said heating operation, and circulating oil from the second mentioned heating operation to the first mentioned heating operation.

6. An improved method of cracking hydrocarbon oils, which comprises circulating the oil in a series of cycles, transferring oil to successive cycles as the tar content of the oil increases, heating the oil to a cracking temperature under pressure by circulating heating gases in heat exchanging relation successively with the oil in the cycles in the order of increasing tar content, subjecting the vapors from the cracking operation to a refluxing operation, returning reflux to a cycle in which the concentration of tar is less than that in the cycle in which the tar content is greatest, and maintaining more rapid circulation in a cycle in which the tar concentration is less than that in the cycle in which the tar concentration is greatest.

7. A process of cracking hydrocarbon oils consisting in passing the oil through a heating coil wherein it is subjected to a conversion temperature, in discharging the heated oil into an enlarged conversion chamber, in passing the vapors issuing from said conversion chamber to a dephlegmator, in returning reflux condensate from the dephlegmator to said heating coil, in condensing the vapors issuing from the dephlegmator and in collecting the resulting distillate, in circulating unvaporized oil from said conversion chamber through an independent heating element wherein it is subjected to a lower temperature than the oil in said coil and back to the conversion chamber, in preventing the return of unvaporized oil which has passed through said independent heating element to said heating coil, and in maintaining a more rapid flow of oil in said heating coil than in said independent heating element.

8. In a process for cracking hydrocarbon oils, the improvement comprising passing the oil to be treated through heating tubes to a vaporizing zone, heating the oil to a cracking temperature in the heating tubes by passing heating gases in indirect heat exchanging relation with the oil therein, taking off vapors from the vaporizing zone and sub-

jecting them to a refluxing operation, passing the reflux at a more rapid rate than that employed in the first said heating operation in heat exchanging relation with the heating gases before the heating gases are brought into heat exchanging relation with the oil in the first said heating operation.

5 In testimony whereof we affix our signatures.
